UNITED STATES PATENT OFFICE.

FELIX GOTTSCHALK, OF NEW YORK, N. Y.

BOOK-CARRIER.

No. 857,050.

Specification of Letters Patent.

Patented June 18, 1907.

Application filed May 19, 1906. Serial No. 317,758.

To all whom it may concern:

Be it known that I, FELIX GOTTSCHALK, a citizen of the United States of America, and a resident of New York, in the county of New York and State of New York, have invented certain new and useful Improvements in Book-Carriers, of which the following is a full, clear, and exact description.

This invention relates to a carrier for books, and more especially to appliances for carrying school books and school supplies.

An object of the invention is to provide a novel rigid book-protecting frame, having in conjunction therewith a strap, band, cord or equivalent encircling device which latter is provided with a buckle or like fastening device, or otherwise adapted to be secured in its proper binding or constricting relation about the frame and books therein, where-
20 by the books or similar articles may be tightly bound together so that they may be conveniently carried and without injury to their edge portions.

Another object is to provide in such a book - carrying device adjustable means whereby equal efficiency of the book-protector and carrier is acquired for a larger or smaller number of books as the case may be, or for book packages of varying shapes and
30 dimensions.

A further object of the invention is to provide a pen and pencil box such as is commonly known as "school box" or "Scholar's Companion," together with convenient means in connection therewith for its attachment to, and detachment from, the carrier. And the invention consists in constructions, combinations, and arrangements of parts, all substantially as hereinafter fully
40 described and set forth in the claims.

In the accompanying drawings.—Figure 1 is a perspective view of the carrier as used in conjunction with a number of school books. Fig. 2 is a perspective view of the carrier empty and in a distended position; and Fig. 3 is a transverse section through the carrier and "school-box," as taken on a line 3—3, Fig. 2. Figs. 4 and 5 are perspective views showing a cord binder which may be employed in place of a buckle fastened strap, such binder having also an arm or shoulder engaging loop.

Similar characters of reference indicate corresponding parts in all of the views.

In the drawings,—A and A' represent the 55 sliding base sections of the carrier, the section A of which has the slideways a formed at opposite edges thereof, and in which are guided the side-edges a' of the section A'.

The surfaces of these sections A and A' 60 preferably have corrugations or ribs a² formed thereon, to give a lateral stiffness or inflexibility thereto, both laterally and longitudinally. These corrugations as formed in the two contiguous slideway sections A 65 and A' are of like cross sectional contour, so as to permit the parts to have a close sliding fit one over and along the other. The section A has a lengthwise extending, centrally located, slot b formed therein in which a 70 downwardly bent lug c formed on the adjacent end portion of section A' slides, and acts as a limiting stop for the same within the end of the slot b.

The outer end portions of the sections A 75 and A', have hinge connected thereto, the foldable end plates C, C, which bear against the edge portions of the books inclosed therebetween and by reason of the rigid, and usually right angular relation that these 80 plates bear to the book edges, no crushing or indenting of the latter by the carrying strap D is caused. Another important purpose of these end plates C and C is for the guidance of the carrying strap D, which, as a reference 85 to the various figures of the drawings illustrates, is passed lengthwise along and under the sections A and A', and thence upwardly at each end of the said sections, and along the outer surfaces of the end plates C, and 90 over the notched upper end portions C' thereof,—if the pile of books is of considerable height as is illustrated in Fig. 1; or through any one of the series of narrow slots d, which are formed in the end plates C C for the accommodation of a pile of books of less height, 95 as Fig. 3 illustrates.

For the accommodation of school children or students, the above described book carrying device may be provided with a box for 100 the reception of pencils, pens, sponges, crayons, etc. The form, or details of construction of this box constitutes no part of this invention, but as usually provided consists of a long narrow and shallow box E, with a sliding cover e. To provide a convenient and secure means of attaching such a box to the base section A of the carrier, I secure at

either end portions of the box E a U-shaped spring metal clip or clasp G. The fastening screws of the clip G are near the lower portions of the spring side members h, thereby permitting the upper end portions of said members to be sprung outwardly from the box sides, as shown in dotted lines in Fig. 3. The upper end portions of the members h have inwardly-bent ends or hooks i formed thereon, which are adapted to engage the outer edge portions of the slideways a of the section A, see Figs. 2 and 3. Adjacent the opposite end portions of the section A, the tops of the overturned slideways a thereof have upwardly struck up, or otherwise formed thereon, the stop lugs k between which lugs the hook like ends of the box clip side members h engage, and thus is prevented any inadvertent dislodgment of the school box from the carrier.

The operation of disengaging the box E from the carrying strap consists, as the description and drawing render apparent, in merely springing outwardly the clamp members h at one side of the carrier until they pass the lugs k. That the box E may engage the section A in as close a manner as possible, when in its attached position, the cover e of said box may be longitudinally channeled or recessed as at m in Fig. 3, thus providing a recess or slideway for the accommodation of the binding and strap D. The carrier with or without the school box in engagement therewith is adapted to be folded and telescoped into small compass, and readily carried in the pocket.

While in the foregoing description the means for constrictively encircling and to be fastened about the book holder frame and its contents has been referred to as a strap provided with a fastening buckle, a band in the form, for instance, of a tape or cord would be to all intents and purposes the equivalent of a strap, and in Figs. 4 and 5 a form of the appliance is illustrated consisting of a cord D having portions extending along the outer face of the base upwardly in engagement with the end pieces and across the open portion of the holder, this cord having a loop D² made therein through which a looped or hitching part d³ is engaged, and whereby it is possible by an easy manipulation to loosen the engagement between the loops D and D³ for letting out the band or cord and for tightening the loop engagement, as required for fastening the parts when the book bundle is properly made up. And the band or cord is furthermore shown as having the extension thereof formed into a large loop D⁴ made with an eye D⁵ for a sliding or running engagement on the standing part of the cord and so that the carrier may be employed as a sling about the arm or shoulder. The shoulder loop D⁴ may be braided, as shown, for the avoidance

of discomfort due to the weight of the book 65 containing holder.

The form of the encircling, securing and carrying appliance shown in Figs. 4 and 5 is one which may be made use of in cases where extreme cheapness of the device is a primary 70 object, although the substitution of one form of binder adapted to be fastened in constriction about the holder for the other is in no sense to be considered as a departure from the spirit and intent of this invention. 75

I claim:—

1. A book carrier consisting of a base, end pieces hinge connected to the opposite ends of the base, to occupy upright positions and also to be foldable on the base, and a strap or 80 like flexible binder arranged along the base, extending upwardly in engagement with the end pieces, and continued over the base, and adapted to tighten the carrier.

2. A book carrier consisting of a base, comprising engaged sections, longitudinally contractible and distensible, the one relatively to the other, and end plates or uprights connected to the extremities of said sectionally formed base, and a strap or like flexible 90 binder extending along the base, also upwardly in engagement with the end pieces, and over the base, and adapted to tighten the carrier. 85

3. A book carrier consisting of a base, end pieces connected to the opposite ends of the base, to occupy upright positions, and having one or more strap or band engagement apertures between their upper and lower edges, and a strap or band arranged along the 100 base, extended upwardly in engagement with the end pieces and over the base, and adapted to be fastened.

4. A book carrier consisting of a base, end pieces connected to the opposite ends of the 105 base, to occupy upright positions and having recesses in their upper edges, and a strap or band arranged along the base, extended upwardly in engagement with the end pieces, and over the base, and serving as a fastener 110 for the carrier.

5. A book carrier consisting of a base, end pieces, connected to the opposite ends of the base, to occupy upright positions and having engagement recesses in their upper edges, 115 and engagement apertures or slots between their upper and lower edges, and a strap or band arranged along the base, extended upwardly in engagement with the end pieces, and over the base, and having fastening 120 means therefor.

6. A book carrier consisting of a base, comprising engaged sections, longitudinally contractible and distensible, the one relatively to the other, means for limiting the endwise 125 movements of said sections, and for preventing the disconnection thereof, and end plates or uprights connected to the extremities of

said sectionally formed base, and a strap or band extending along the base, also upwardly in engagement with the end pieces, and over the base, and serving to tighten 5 and fasten the device.

7. A book carrier consisting of a base, comprising engaged and relatively longitudinally contractible and distensible sections, one thereof being constructed with marginal longitudinal overturned lips, within which the edge portions of the other section are engaged, and end plates or uprights connected to the extremities of said sectionally formed base, and a strap or band arranged along the 10 base, also extending upwardly in engagement with the end pieces, and over the base, and serving to tighten and fasten the device.

8. A book carrier consisting of a base, comprising engaged and relatively longitudinally contractible and distensible, thin metallic sections, one thereof being constructed with marginal longitudinal overturned lips, within which the edge portions of the other section are engaged, and both said sections being 20 constructed with matching longitudinally extending corrugations, and end plates or uprights hinge connected to the extremities of said sectionally formed base, and a strap or band arranged along the base, also upwardly in engagement with the end pieces, and over the base, and provided with tightening means.

9. A book carrier consisting of a base comprising engaged and relatively longitudinally contractible and distensible thin metallic sections, one thereof being constructed with marginal longitudinal overturned lips within which the opposite edge portions of the other section are engaged, and one of said sections 35 having a longitudinal slot between its edges and terminating within its ends, and the other section having a projection extended within said slot, end plates or uprights hinge-connected to the extremities of said sectionally formed base, and a strap or band arranged along the base and also extended upwardly and engaging with the end pieces and continued over the base, and adapted to be fastened in its encircling relation.

50 10. A book carrier consisting of a base, end pieces hinge connected to the opposite ends of the base, and a strap or band arranged along the base, extending upwardly in engagement with the end pieces, and continued over the base and having a fastening means, and a box, and means of detachable connection between the box and base, whereby said box may be supported by the carrier and at pleasure detached therefrom.

60 11. A book carrier consisting of a base, end pieces hinge connected to the opposite ends of the base and a strap or band arranged along the base, extending upwardly in engagement with the end pieces, and continued

over the base, and having fastening means, 65 and having combined therewith a box provided at opposite sides with one or more pairs of members constructed with inturned extremities to engage on, and acquire supporting engagements at, the marginal portions of the base.

7. A book carrier consisting of a base comprising engaged and relatively longitudinally contractible and distensible thin metallic sections, one thereof being constructed with marginal longitudinal overturned lips within which the opposite edge portions of the other section are engaged, and one of said longitudinal lips having projections struck up therefrom near opposite ends thereof, end 75 plates or uprights hinge connected to the extremities of said sectionally formed base, and a strap or band arranged along the base and also extended upwardly and engaging with the end pieces and continued over the base 80 and adapted to be tightened and fastened, and a box provided at opposite sides with pairs of members constructed with inturned extremities to engage over the longitudinal overturned lips of one of said base sections, 90 and said members being capable of lateral deflections, for the purpose explained.

12. A book carrier consisting of a base comprising engaged and relatively longitudinally contractible and distensible thin metallic sections, one thereof being constructed with marginal longitudinal overturned lips within which the opposite edge portions of the other section are engaged, and one of said longitudinal lips having projections struck up therefrom near opposite ends thereof, end 95 plates or uprights hinge connected to the extremities of said sectionally formed base, and a strap or band arranged along the base and also extended upwardly and engaging with the end pieces and continued over the base 100 and adapted to be tightened and fastened, and a box provided at opposite sides with pairs of members constructed with inturned extremities to engage over the longitudinal overturned lips of one of said base sections, 105 and said members being capable of lateral deflections, for the purpose explained.

13. In a device of the character described, the combination with a base consisting of two sections constituted of thin metallic strips, 110 made with longitudinal matching corrugations, one of said base sections having a longitudinal slot terminating within the ends thereof, and the other section having a lip angularly turned therefrom and engaging in 115 said slot, and one of said sections being furthermore constructed with longitudinally extending edgewise located overturned ears within which the edge portions of the other section have sliding engagements, of end 120 plates hinge-connected to the outer ends of said base sections and provided with transverse strap engagement slots between their upper and lower ends and having in their upper ends strap engagement notches or recesses, a strap or band ranging along under the sectionally formed base, extended upwardly outside of said end plates and adapted to engage as desired, either through the end plate slots or across the recessed upper 125 ends of the end plates, and to be continued over the base, and provided with a securing appliance.

14. The combination with a book carrier consisting of a base, upright end pieces connected to the opposite ends of the base, and a strap or band arranged along under the base, extending upwardly in engagement with the end pieces, and continued over the base, and having a fastening means therefor, of a box 130 to be supported by and under the base, means for detachably connecting the box to the base,—and said box having a cover con-

structed at its top with a longitudinal channel for the accommodation of the strap.

15. A book carrier consisting of a base, comprising engaged sections, longitudinally contractible and distensible the one relatively to the other, and end plates or uprights hinge connected to the extremities of said sectionally formed base, and a flexible binder extending along the base, also upwardly in engagement with the end pieces,

and over the base, and adapted to serve as a fastening for the carrier, and said binder having an arm or shoulder engagement loop.

Signed by me at New York, N. Y., in presence of two subscribing witnesses.
